UNITED STATES PATENT OFFICE

ROBERT B. ADAMS, OF LONSDALE, RHODE ISLAND

ROOFING SHINGLE

Application filed January 4, 1928. Serial No. 244,460.

This invention relates to flexible roofing shingles, and has more particular reference to improvements in the type of shingle shown in my U. S. Patent No. 1,636,349, dated July 19, 1927.

5 The primary object of the present invention is to improve the form of shingle shown in my above mentioned patent, whereby a greater lapping area and better nailing surface is provided.

10 A further object of the invention is to provide a shingle which, by reason of the design thereof, may be readily and economically cut from a strip of roofing material with a minimum of waste.

15 A still further object is to provide novel means for properly spacing the shingles while laying the same, and at the same time to provide improved means for fastening the outer and free ends of the exposed shingle extensions to the body portions of the shingles directly below said extensions, in order to prevent the outer ends of said extensions from curling upward under the 20 action of the elements, whereby more complete protection is afforded.

25 The invention consists in the novel form, combination and arrangement of parts hereinafter more fully described, shown in the accompanying drawing and claimed.

30 In the drawing:

Figure 1 is a plan view of a portion of a roof covered with shingles constructed in accordance with the present invention;

35 Figure 2 is a bottom plan view showing a pair of twin shingles constructed in accordance with the present invention, in interlocked operative relation;

Figure 3 is an enlarged section on line 40 3-3 of Figure 1;

Figure 4 is a diagrammatical plan view showing how the present shingles can be economically cut from a strip of flexible roofing material;

45 Figure 5 is a detailed plan view of one of my improved twin shingles; and

Figure 6 is a detailed plan view of a single shingle constructed in accordance with the present invention.

50 As shown in the several views, each shingle

or shingle unit comprises a rectangular body portion 5 of a suitable or desired width, and an extension 6 on and centrally of the lower edge of the body portion 5, the extension 6 being integral with the body portion and preferably substantially triangular in shape with the side edges thereof sloping at an angle of substantially 45° to the longitudinal axis of the body portion 5.

55 The length of each triangular extension 6 is preferably somewhat less than the width of the body portion 5, and the width of the base of each extension 6 is preferably slightly less than the length of the body portion 5, the extensions being slightly spaced from the ends of the body portion 5 as shown at 7.

60 The apex of the triangular extension 6 is preferably blunted as at 8, integrally formed on this blunt apex edge of the triangular extension 6 is an arrow head tab 9 having a 65 relatively wide squared nose 10.

65 Slat-like flaps 11 are integrally formed on the sloping side edges of the extension 6, which correspond to the slats 12 in my above mentioned patent, and which are adapted to 70 be under-turned on the fold lines 12 as set forth in my said patent.

75 As indicated in Figure 4, shingles of the above design may be readily cut from strip roofing material with practically no loss of 80 material, other than the small punchings made by cutting substantially triangular notches as at 13 to define the basis of the arrow head tabs 9 and to separate the same from the adjacent ends of the flaps 11. It 85

will also be noted that by providing the arrow head tabs 9 with squared noses, recesses will be formed as at 14 to space the extensions 6 at uniform distances from the ends of the body portion 5 and provide shoulders 90 at the points 7 which are transversely aligned, so that the arrow head tab of one shingle may be under-turned about the shoulders 7 at adjacent ends of adjoining shingles as taught in my above mentioned patent. By dividing 95 the strip of roofing material as at 15 at right angles to the length of the shingles and at points intermediate alternate ones of the extensions 6, twin shingles will be formed as

100 shown in Figures 1, 2, 4 and 5, and by addi-

tionally similarly severing the strip of roofing material as indicated by dotted lines at 16 in Figure 4, single shingles of the form shown in Figure 6 may be had.

5 It will be particularly noted that by forming the shingles with rectangular body portions, a greater lapping area will be had than by providing the body portion of the shingle with sloping or upwardly converging end 10 or side edges as indicated at 2 and 3 in my above mentioned patent, while considerable waste of material will be avoided. Moreover, by providing the arrow head tabs 9 with squared noses, a better nailing surface will 15 be provided for said arrow head tabs, thereby facilitating laying and nailing of the shingles and effecting a more secure fastening of the same than is had with the provision of pointed nosed arrow head tabs as disclosed 20 in my above mentioned patent.

The manner of laying, assembling and fastening the shingles is substantially the same as explained in my above mentioned patent, except that the nails 17 will be driven at a 25 plurality of points adjacent the upper edge of the body portion 5 instead of at a single point substantially midway between the sides or ends of the body portion, the nails 15* being driven through the arrow head tabs 9.

30 It might be noted, however, that in laying the shingles "a starter" 18, comprising a plain strip of roofing material of the same width as the width of each single or twin shingle, is nailed along the lower edge of the roof. The 35 lower row of shingles are then nailed end to end directly over the starter 18 with the blunt edges 8 of the extensions 6 flush with the outer or lower edge of said starter. The starter 18 is provided for the purpose of filling the spaces between extensions in the lowest row of shingles. The flaps 11 are overturned, and the arrow head tabs 9 are turned under the lower edge of the starter, the nails 15* being driven through the starter and the 40 arrow head tab before the shingle proper is folded upwardly and downwardly onto the roof for being nailed at 17. The arrow head tabs 9 of the shingles of the next upper row are then inserted under the shingles of 45 the lower row at the shoulders 7, and nailed as at 15*, whereupon said next row of shingles are laid onto the roof and nailed as at 17. This procedure is repeated for subsequent 50 rows of shingles, and it will be seen that the extensions 6 will be effectively fastened 55 rows of shingles, and it will be seen that the extensions 6 will be effectively fastened against curling upward.

What I claim as new is:—

1. A flexible roofing shingle comprising a 60 rectangular body portion having straight parallel end edges and formed on its lower edge with an integral triangular extension having downwardly converging side edges and terminating in a relatively narrow blunted apex, and a relatively small square-nosed 65 arrow head tab integrally formed on the

blunt apex edge of said extension, said shingle having folding side flanges which provide lateral shoulders for the arrow head tabs of shingles of the next upper course to seat against.

2. A flexible roofing shingle comprising a rectangular body portion having straight parallel end edges and formed on its lower edge with an integral triangular extension having downwardly converging side edges and terminating in a relatively narrow blunted apex, and a relatively small square-nosed arrow head tab integrally formed on the blunt apex edge of said extension, said triangular extension being of a length less than the width of the body portion and being slightly spaced from the ends of the body and formed with folding side flanges which provide shoulders for the arrow head tabs of shingles of the next upper course to seat against.

In testimony whereof I affix my signature.
ROBERT B. ADAMS.
